FIREARM MAGAZINE

Earl M. Stukas, Clinton, Iowa

Application April 5, 1949, Serial No. 85,691

1 Claim. (Cl. 42—50)

1

It is among the objects of the invention to provide an improved cartridge magazine including spring means for holding cartridges in position to be moved by the gun breech mechanism from the magazine into the receiver of the gun, wherein the magazine has a side opening through which a charge of cartridges can be rapidly inserted and is provided with means for locking the cartridge feeding spring means out of the way while the magazine is being charged; in which a slidable cover is provided for the side opening in the magazine and in which the features providing the rapid charging arrangement may be applied to an existing magazine or incorporated in a new magazine and will not interfere, in any way, with the use of the magazine in a gun for which the magazine is designed; will not interfere with the normal feeding of the cartridges from the magazine, and will greatly facilitate the insertion of a first charge of cartridges into the magazine, especially under adverse conditions, such as cold or wet weather, or limited time, and in which the modified magazine is strong and durable in construction and is little, if any, more expensive to manufacture than a conventional magazine of the same size and type.

Other objects and advantages will become apparent from a consideration of the following description and the appended claim in conjunction with the accompanying drawing, wherein:

Figure 1 is a side elevation of a conventional firearm, shown in broken lines, with a magazine illustrative of the invention, shown in full lines, operatively positioned therein;

Figure 2 is a side elevation on a somewhat enlarged scale of the magazine illustrated in Figure 1;

Figure 3 is a front edge elevation of the magazine;

Figure 4 is a side elevation of the magazine showing the side opposite that shown in Figure 2;

Figure 5 is a longitudinal cross-section taken on the line 5—5 of Figure 3;

Figure 6 is a longitudinal cross-section of a fragmentary portion of a magazine taken substantially on the line 6—6 of Figure 2; and

Figure 7 is a longitudinal cross-section of a fragmentary portion of the magazine taken substantially on the line 7—7 of Figure 2 with the movable parts of the magazine in a different position from that illustrated in Figure 6.

With continued reference to the drawing, the magazine comprises an elongated, flattened tube 10 of generally rectangular cross-section having an internal width slightly greater than the length

2

of a cartridge to be received therein, and an internal thickness slightly greater than the diameter of such a cartridge. This flattened tube is provided in one side wall with a rectangular opening 11 having a width substantially equal to the length of a cartridge, and a length substantially equal to the length of the cartridge storage space in the magazine, and is provided in its opposite side wall with an elongated slot 12 having a length slightly greater than the length of the cartridge storage space in the magazine and having at one end a circular enlargement 13. An end wall 14 closes one end of the tube 10 and projects outwardly at the forward edge of the tube, as indicated at 15, to provide a tongue for facilitating the movement of the magazine into and out of the magazine-receiving space in the stock or grip 16 of the gun. The magazine tube 10 is open at its opposite end and is provided with inturned lips 17 which retain the cartridges in the magazine and position the top cartridge in the magazine to be engaged by the breech mechanism of the gun and moved from the magazine into the receiver of the gun through the opening 18 in the front side of the magazine at the upper end of the latter.

A follower 19, which may be in the form of a substantially rectangular block, is slidably mounted in the magazine tube and a coiled compression spring 20 is disposed between this follower and the end wall 14 of the magazine to resiliently urge cartridges in the magazine toward the open end of the latter.

A button 21 has a shank 22 which extends through the slot 12 and through an aperture in the follower 19 into a recess 23 provided in the follower where the shank is riveted over to firmly secure the button to the follower. The riveting may be performed through an opening 24 provided in the side wall of the magazine tube between the opening 11 and the end wall 14. The button has a substantially circular shoulder 25 bearing against the side of the follower 19 opposite the recess 23, and has a head 26 spaced outwardly of the shoulder 25 by an annular reduction 27, the shoulder 25 having a diameter substantially equal to the diameter of the circular enlargement 13 at the end of the slot 12 adjacent the end wall 14, and the annular reduction 27 having a diameter substantially equal to the width of the remainder of the slot.

The head 26 of the button is used as a grip for sliding the follower 19 in the tube 20 in a direction to compress the spring 20. When the spring has been compressed to an extent such that the

shoulder 25 is in registry with the enlargement 13 at the end of the slot, the button is pulled outward sufficiently to seat the shoulder in the enlargement, as illustrated in Figure 7, to releasably lock the follower in its fully retracted position at the bottom of the cartridge storage space in the magazine.

The end of spring 20 is extended upwardly and curved to provide a loop 28 between the follower 19 and the side wall of the tube opposite the slot 12 which loop resiliently urges the follower toward the side wall in which the slot is provided to assist in seating the shoulder 25 in the slot enlargement 13. When the head 26 of the button is pressed inwardly against the force of spring loop 28, shoulder 25 will be moved out of enlargement 13 and the follower released.

The magazine tube 10 is provided along the longitudinal edges of the side opening 11 with pairs of spaced-apart notches which provide respective tongues 30 between the two notches of each pair. These tongues are raised somewhat above the remaining portions of the tube side wall along the edges of the opening 11 to provide guideways along the opposite, longitudinal edges of the opening, and a flat, substantially rectangular cover plate 31 is slidable in these guideways to cover and uncover the opening 11. This plate 31 is turned outwardly at one end to provide a flange 32 affording a finger grip for sliding the cover plate in the guideways.

In order to charge the magazine, the follower 19 is moved toward the end wall 14 by the button 21 until the shoulder 25 of the button registers with the enlargement 13 at the end of the slot 12, whereupon the button is pulled outwardly to seat the shoulder in the enlargement and thus releasably lock the follower in retracted position and the cover plate 31 is then slid in a direction to uncover the opening 11. The proper number of cartridges is then dropped into the magazine through the side opening 11, whereupon the cover plate 31 is slid relative to the magazine in a direction to cover the side opening, and the button 21 is pressed inwardly to release the shoulder from the slot enlargement 13, to thereby release the follower to resiliently urge the cartridges toward the open end of the magazine.

With the magazine of the invention, a full charge of cartridges can be inserted in an extremely short time, particularly as compared with the length of time required to insert the cartridges one-by-one into the open end of a conventional magazine.

The invention may be embodied in other specific forms without departing from the spirit or essential characteristics thereof. The present embodiment is, therefore, to be considered in all respects as illustrative and not restrictive, the

scope of the invention being indicated by the appended claim rather than by the foregoing description, and all changes which come within the meaning and range of equivalency of the claim are, therefore, intended to be embraced therein.

What is claimed is:

A cartridge holding magazine for a firearm comprising a thin-walled hollow body of substantially rectangular shape and having flat side walls disposed in spaced apart and substantially parallel relationship, an end wall closing one end thereof and a cartridge retaining lip formation at the other end thereof, a cartridge follower disposed in said body and movable longitudinally thereof, a compression spring disposed in said body between said follower and said end wall resiliently urging said follower toward said lip formation, one of said side walls having a longitudinally extending slot therein terminating in an enlargement at its end adjacent said end wall, a button secured to said follower and projecting through said slot, said button having a shoulder thereon engageable in said slot enlargement to releasably retain said follower in a position adjacent said end wall against the force of said spring, the other side wall of said body having an elongated opening therein for the insertion of cartridges into said magazine body while said follower is retained in position adjacent said end wall, a cover plate for said opening disposed against said other side wall, and means carried by said other side wall and engaging said cover plate securing said cover plate to said body for sliding movement relative to said body into and out of covering relationship to said opening, said means comprising tongues on said other side wall spaced apart along the longitudinal edges of said opening and engaging said cover plate adjacent the longitudinal edges of the latter.

EARL M. STUKAS.
